SKIN FASTENER

Frank C. Wallace, Los Angeles, Calif., assignor,
by mesne assignments, to Herman H. Helbush,
Beverly Hills, Calif.

Application November 3, 1942, Serial No. 464,361

5 Claims. (Cl. 85—5)

This invention relates to skin fasteners and, more particularly, it has to do with fasteners employed in the nature of temporary rivets for holding together perforated superposed sheets or the like during riveting operations.

In the main my present improvements are directed to novel structural features which substantially simplify and reduce the cost of manufacture of skin fasteners of this type as well as increase their operating efficiency. This type of fastener typically employs a cylindrical housing in which is reciprocally mounted a spring-pressed bifurcated retaining pin which has a laterally projecting portion on its outer end for engaging and clamping work against the end of the housing. The bifurcations have generally been provided in prior art devices in several different manners. In one type the pin is longitudinally slotted from its outer end to provide the bifurcations; in another type the pin is composed of two separable segments. In still another type the retaining member is in the form of a relatively long resilient member bent into hairpin shape, the closed end of which projects from one end of the housing to be directly engaged and pressed inwardly of the housing by an applying tool to protract the opposite sheet engaging end from the housing. The first two types are relatively expensive to manufacture and the last-mentioned type is unsatisfactory because, among other reasons, the retaining member must be made of such small cross-section that it becomes objectionably distorted when sufficient end pressure is applied to compress the spring normally urging the retaining member into retracted position.

To make my invention fully understood I shall now describe a preferred adaptation of it although, within its broader scope as defined by the appended claims, the invention is susceptible of being carried out in other specific forms of device and I therefore do not wish to be limited to the specific details now to be described except to the extent that some of the claims may recite those specific details.

For the purposes of the following explanation I shall refer to the accompanying drawing, in which:

Fig. 1 is a side elevation of my clamp device with the retaining member in retracted position;

Fig. 2 is a longitudinal sectional view showing the retaining member in protracted position;

Fig. 3 is a section on line 3—3 of Fig. 2;

Fig. 4 is a plan view of Fig. 1 with parts broken away;

Fig. 5 is a section on line 5—5 of Fig. 2; and Fig. 6 is an end view taken on line 6—6 of Fig. 1.

Referring now to the drawing, I show at 5 a cylindric body having an end wall 6 provided with a central opening 7. The body is provided with an annular flange 10 presenting an undercut shoulder 11 adjacent the inner end, which shoulder enables the clamp to be held against longitudinal movement in a clamp applying tool, not shown, as will be hereinafter described.

Reciprocally mounted in the body bore I provide an elongated bar or plunger 17 having its outer end headed at 18 for engagement by an applying tool, not shown, the inner end of the bar being provided with a transverse hole 22 spaced somewhat from its inner end. A somewhat U-shaped retaining member 20, made of a resilient material and presenting at the outer end of each of its legs a radial projection 20a, has its closed end mounted in hole 22, member 20 being passed through hole 22 before being bent into the U-shape illustrated.

An end cap 30 is secured over the inner end of the body in position spaced from the end wall 6, 25 by having its peripheral edge crimped into an annular groove provided in the body. To spread the legs of member 20 apart I provide a flat T-shaped spreader 35 having its cross portion 35a rotatably mounted in the space between cap 30 and end wall 6, the central leg 35b of the spreader projecting outwardly between the legs of member 20 through an opening 37 provided in the cap.

A coil spring 40 is mounted around the retaining member 20 and bar 17 within the body, seating at its inner end against end wall 6 and seating at its outer end against head 18 of bar 17, this spring normally urging the retaining member into retracted position (Figs. 1 and 4).

The operation of the device is as follows: First 40 the device is placed in an applying tool, not shown, many of which are well known in the art. Such a tool holds the body 5 against longitudinal movement while exerting inward pressure on bar 17 to protract the outer end of retaining member 20 with respect to the body. When the device is thus fully protracted (Figs. 2 and 3), the outer end of member 20 is spaced sufficiently beyond the outer end of the spreader leg 35b to enable the legs of the retaining member to flex together so that their enlarged outer ends may be

50 inserted through registering perforations P in work sheets S. Upon release of the pressure on the end 18 of the bar, the spring 40 retracts the legs of member 20 inwardly of the body while 55 those legs are spread apart by the longitudinally

stationary spreader 35, causing the projections 20a to engage the sheet S farthest from the cap 30 and resiliently clamp the sheets between projections 20a and the outwardly vaulted sheet engaging end surface of the cap.

By the structure described, the retaining member 20 may be made of as small cross-section as desired since it is relatively short and does not have to receive directly the considerable distorting pressure applied by the applying tool to compress spring 40. The push bar 17 may be made as strong as desired to enable it to be engaged by the operating tool and in turn protract the retaining member. Push bar 17 preferably extends into the bore of the housing, when the retaining member is retracted, a distance at least equal to the length of travel of the retaining member in moving between protracted and retracted positions. Since pliers type applying tools are frequently used to push the bar inwardly against the spring pressure and since the pressure applying body of such tool does not move in a straight line but rather about an arc, the utility of the relatively strong push bar and its extent are readily appreciated. It can also be readily observed that if the U-shaped retaining member were made sufficiently long to enable its closed end to project outwardly from the inner end of the housing to directly receive the pressure of the applying tool instead of utilizing bar 17, fatal distortion would result because as a rule these retaining members must be made of extremely small cross-section. For instance, in the general use to which such devices are being put in the airplane industry at this time, the combined cross-section of both legs of the retaining member and the spreader leg 35b must be sufficiently small to permit them to pass through a sheet perforation of diameters of the order of $\frac{1}{8}''$ to $\frac{1}{4}''$.

Bar 17 and the closed end of retaining member 20 are pivotally connected together so that the bar may swing about the end of the retaining member. Thus although the operating tool may move the outer end of the bar laterally, the lateral movement is not imparted to the retaining member, which latter is at all times free to move in and out of the body in a straight line.

I claim:

1. A skin fastener of the class described comprising a body presenting a sheet engaging outer end portion, a U-shaped retaining member having its closed end within the body and its legs projecting through the sheet engaging end portion of the body for protraction and retraction with respect thereto, means for protracting and retracting the retaining member including a spring pressed elongated push member pivotally secured at its inner end to the closed end of the retaining member and projecting from the other end of the body for engagement by an operating tool.

2. A skin fastener of the class described comprising a body presenting a sheet engaging outer end portion, a U-shaped retaining member having its closed end within the body and its legs projecting through the sheet engaging end portion of the body for protraction and retraction with respect thereto, means for protracting and retracting the retaining member including a spring pressed elongated push member secured at its inner end to the closed end of the retaining member and projecting from the other end of the body for engagement by an operating tool, and means for spreading the legs of the retain-

ing member apart including a T-shaped spreader bar anchored against longitudinal movement in the body and projecting outwardly therefrom between the legs of the retaining member.

3. A skin fastener of the class described comprising a cylindric body having an end wall at one of its ends, said end wall being provided with an opening, a U-shaped retaining member having its closed end in the body and its legs projecting through said opening and protractable and retractable with respect to the end wall, laterally projecting means on the outer ends of the legs for engagement with work to be fastened, means for moving the retaining member into protracted and retracted positions including an elongated push bar connected at its inner end to the closed end of the retaining member and projecting from the opposite end of the body for engagement by an actuating tool and spring means normally urging the push bar outwardly of the body, said push bar extending into the body when the retaining member is in retracted position, a distance at least as great as the length of travel of the retaining member in its movement between protracted and retracted positions.

4. A skin fastener of the class described comprising a cylindric body having an end wall at one of its ends, said end wall being provided with an opening, a U-shaped retaining member having its closed end in the body and its legs projecting through said opening and protractable and retractable with respect to the end wall, laterally projecting means on the outer ends of the legs for engagement with work to be fastened, means for moving the retaining member into protracted and retracted position including an elongated push bar pivotally connected at its inner end to the closed end of the retaining member and projecting from the opposite end of the body, a head on the projecting end of the bar and a coil spring seating at its inner end against the body end wall and seating at its other end against said head whereby normally to urge the bar outwardly of the body and the retaining member into retracted position, said spring closely surrounding the point of pivotal connection of the bar to the retaining member whereby to limit the relative movement of said members with respect to each other.

5. A skin fastener of the class described comprising a cylindric body open at one end and having an end wall at its opposite end, said end wall being provided with an opening, an elongated push bar disposed longitudinally in the body and projecting from the open end thereof for engagement by an actuating tool, a transverse hole through the inner end of the bar, a U-shaped retaining member having its closed end mounted in said hole and its legs projecting through the opening in the end wall for protraction and retraction with respect thereto, laterally projecting means on the outer ends of the legs of the retaining member for engagement with work to be fastened, spreader means carried by the body and disposed between said legs, said spreader means being held against longitudinal movement with respect to the body whereby upon movement of the legs relative to the body the legs are spread apart, and a coil spring surrounding the inner end of the retaining member and the bar, said spring normally urging the bar outwardly of the body.

FRANK C. WALLACE.
